TELEPHONE SYSTEM

Karl L. Burgener, Villa Park, Ill., assignor to Automatic Electric Laboratories, Inc., Chicago, Ill., a corporation of Delaware

Application August 4, 1944, Serial No. 548,077

9 Claims. (Cl. 179—27)

This invention relates to telephone systems in general, but is more particularly concerned with automatic telephone systems in which both main exchanges and branch exchanges are employed; and the broad general object, briefly stated, may be said to consist of the provision of new and improved circuit arrangements for a two way trunk circuit connecting branch and main exchanges.

In prior art, use has been made of a polarized relay bridged across the trunk circuit to operate and busy the trunk at the banks of the outgoing switches, after seizure in the main exchange by an automatic switch or by an operator in a manual main exchange. Another method which has been employed is to bridge across the trunk a high resistance relay at the branch exchange. A still further method has been to connect a relay from one trunk conductor to ground at the branch exchange.

This invention provides in the branch exchange a relay which is normally connected from the ground side of the trunk to battery at the branch exchange. However during each call over the trunk in either direction, the relay is during certain periods, bridged across the two trunk conductors and is operated by current flowing over the trunk from the main exchange. The relay will operate and perform its functions regardless of the direction of flow of said current.

One of the objects of this invention is to provide improved means for instantly busying the trunk circuit at the branch exchange when a switch in the main exchange seizes the trunk circuit or when an operator in a manual exchange seizes the trunk.

Another object of this invention is to provide means for guarding the trunk circuit against intrusion during the period of time between actual seizure by the main exchange and the start of the ringing period, which follows seizure, for operating the answering signal to attract the branch operators' attention.

Another object of this invention is to provide means for guarding the trunk circuit against intrusion during the period between the actual completion of the conversation and the return to normal of all of the elements in the trunk circuit.

A feature of this invention is the provision of means for connecting ground to one of the trunk conductors to close a circuit for operating the line equipment in the main exchange to cause said line equipment to seize a trunk leading to an idle selector at the main exchange.

Another feature of this invention is the provision of means for preventing the branch exchange subscribers from completing calls to the main exchange numbers in specified groups by including means for opening the trunk circuit, placing ground on one conductor of the main exchange section of the trunk, alternately connecting the high resistance relay from battery to the other conductor and across the two conductors, to guard the trunk from intrusion until the calling subscriber abandons the unauthorized call. A distinctive tone may be introduced onto the calling subscriber's line at this time by the adapter to remind the calling party that his line is connected to an unauthorized number.

Another feature of this invention is the provision of a non-ring-through repeating coil to prevent ringing current from reaching the operator's receiver in the event that the answering plug was inserted into the jack during the ringing period, however after the plug has once been placed in the jack in answering an incoming call or in the event that a patching cord is placed in the jack to connect the trunk direct to a subscriber's line, the novel circuit arrangements permits the ringing current from the main exchange to bypass the repeating coil to directly ring a supervisory relay in the cord circuit or to ring directly onto the line of the called subscriber. In ringing in on the supervisory relay the main exchange operator can recall the branch exchange operator.

The foregoing objects and features together with others not specifically mentioned will be explained in detail hereinafter, with reference to the drawings comprising Figures 1, 2, 3 and 4. The drawings show by the usual circuit diagrams a sufficient amount of the equipment in a telephone system embodying the invention to permit the invention to be readily explained and understood. The drawings should be arranged horizontally in numerical order with Fig. 1 at the left.

The apparatus shown in Fig. 1 is a skeleton key and cord circuit of a private exchange attendants switchboard to show the normal condition of a loop across the tip 164 and ring 162 of the plug. When the branch exchange operator inserts plug P1 into jack J2 a loop is placed across the branch exchange section of the trunk. Fig. 2 is the trunk circuit comprising conductors 257 and 258. The branch exchange end has two branches, one terminates in the jack J2 which is used mostly for answering main to branch exchange calls, although it may be used by the

operator for the purpose of extending special calls from the branch to the main exchange. This jack may also be used with patching cords to extend the trunk line direct to one of the branch exchange subscribers' lines, for night service or special cut-through day service. The main exchange end also has two branches, one branch to the regular line equipment for calls incoming to the main exchange from the branch exchange and the other branch to multiple bank contacts for outgoing calls from main to branch exchange. Fig. 4 is a skeleton of the main exchange circuits showing the trunk terminating in a line equipment for the incoming calls and, in multiple switch bank contacts for the outgoing calls from main to branch exchange.

When the trunk circuit is taken into use at the main exchange of the automatic type, a connector seizes the trunk and supplies ground and battery from the ring cut-off relay to the two sides of the trunk line. Ground, over one side of the trunk from the ring cut-off relay, operates the high resistance relay to place a guarding potential on the selector bank multiple in the branch exchange and to light the busy lamp. Following seizure, ringing current is superimposed on the trunk line to operate an alternating current relay at the branch exchange to signal the operator by lighting the answer lamp. When the branch exchange attendant answers the call, the circuit will be closed through a loop in the cord circuit causing the ring cut-off relay to operate and complete the talking circuit from the calling subscriber to the attendant cabinet operator.

As the ringing current is applied intermittently to the circuit there is a so called ringing period and a silent period. By providing the high resistance relay connected from battery to the ground side of the trunk line, this relay will operate practically simultaneous with the seizure by the connector at the main exchange. Thus the trunk will be guarded from the instant it is seized by the main exchange connector regardless of the condition of the ringing source, as to whether it is in the ringing or the silent period. The winding of this relay is of such a character that it can operate from ground through one winding of the ring cut-off relay without causing said ring cut-off relay to operate. The busy lamp on the attendants switchboard will light when the trunk is seized but the answer lamp will not light until after the ringing current from the connector is superimposed in bridge on the trunk, causing the alternating current relay to operate and close the circuit to the answering lamp.

After a conversation has been terminated both calling and called parties will open their line circuits by hanging up their receivers and the switch train in the central office will restore to normal immediately, if the connector is of the first party release type. This means that the connector will restore before the operator could remove the plug from the jack and means must be provided to guard the main exchange end of the trunk for a period of time until the operator frees the branch exchange end. This is accomplished by the novel circuit arrangement of the trunk whereby the release of the trunk by the connector in the main exchange, causes a relay in the trunk circuit to operate opening the ground side of the trunk to the attendants switchboard and placing a ground on the battery side of the trunk to the main office, thus immediately operating a line equipment in the main office placing a guard on the trunk circuit. When the operator removes the plug from

the jack at the attendants switchboard thus freeing the branch exchange end of the trunk circuit, the line equipment at the main exchange will immediately restore making the trunk available for calls in either direction.

Should the branch exchange operator remove the plug before the release of the connection in the main office, the branch exchange end of the trunk must be guarded from seizure by a subscriber making an outgoing call. This is accomplished by a novel feature of the circuit which causes the high resistance relay to be bridged across the trunk circuit and held in operated position by direct current from the main exchange which current may be in either direction. This relay in turn causes the busy condition to be maintained on the multiple bank contacts of the automatic switches in the branch exchange and also causes the busy lamp to glow to indicate the busy condition to the branch exchange operator. The trunk circuit will remain in this condition until current is removed from the main exchange end of the trunk circuit to allow the high resistance relay to operate to release other relays and restore the trunk circuit to its normal condition and make the circuit available to calls in either direction.

A particular advantage of bridging the high resistance relay across the trunk circuit, under the conditions where calling main exchange—either automatic or manual—has not released even though the branch exchange has released, is that the main exchange end of the trunk may be attached to a manual switchboard or to any one of several types of automatic systems or to a "Toll" switchboard, and the various circuits involved are dissimilar. There are instances where the current flow from the main exchange is in the normal direction of ground on positive line and battery on negative line when the call is first established and at a later stage the current flow is in the exact opposite direction. The high resistance relay, when connected as a bridge at the branch exchange end, will be energized in either instance and therefore this trunk circuit is more universal in its application than the circuits heretofore used.

Other objects and features of this invention are concerned mainly with circuit details which will be explained hereinafter with reference to the accompanying drawings, which show by means of the usual circuit diagrams the essential features of the invention. The trunk circuit is illustrated in Figs. 2 and 3 and the associated circuits Figs. 51 and 54. It is assumed that conductors 257, 258 and 259 are a set of bank contacts to which the branch exchange subscribers have access by dialing through a regular train of automatic switches. Fig. 1 is a part of the branch exchange attendants' cord cord circuit to show the closed loop from the plug tip 161 through one winding 173 of the repeating coil, contact 111, relay 120, contact 112, one winding of repeating coil 174 to ring 162 of the plug. Fig. 4 is a portion of the main exchange circuits, indicating that the trunk circuit conductors 463 and 464 have two branches, one branch terminating in multiple contacts of well known Strowger switch banks through which the main exchange subscribers have access to the trunk line leading to the branch exchange and the other branch terminating in a regular line switch equipment through which the branch exchange subscribers have access to the main exchange subscribers. It should be noted that while the line equipment shown is of the well known type, there

is a slight change in the connections, ground has been removed from one spring of relay 410 with the result that, when this relay is in its normal position, contact 411 will not connect with ground, therefore trunk conductor 463 is free from ground when the trunk circuit is normal. Should this trunk terminate in a manual main exchange the terminating equipment would have circuit characteristics similar to those described herein as applying to the automatic system.

Fig. 3 illustrates the discriminating feature, indicating a method of preventing the branch exchange subscriber from completing, by dialing, a connection through this trunk circuit to unauthorized numbers, and further means for opening the trunk circuit and connecting the high resistance relay from conductor 463 to battery under certain conditions, and under other conditions connecting said relay across the outgoing section to guard the main exchange end until the calling branch exchange subscriber abandons the call.

It will be noted that the branch exchange end of the trunk circuit also has two branches, one branch terminating in the multiple bank contacts 257, 258 and 259, through which the branch exchange subscribers have access to the group of trunks leading to main exchange, it will be assumed that Fig. 2 illustrates one trunk, in such a group. The other branch terminates in a jack on an operator's position in a branch exchange switchboard or attendant's cabinet. This branch is equipped with the ordinary lamp signals to indicate incoming calls and busy conditions on outgoing calls, and the usual jack into which the operator may insert a plug in answering incoming calls or for establishing outgoing calls to the main exchange, or for a patching cord by which a subscriber's line may be connected direct to a trunk for night use or for any other special service. The main exchange may be manual or automatic and when the latter, the operator completes the call by use of a dial, which is part of an operator's circuit (not shown).

In connection with the drawings it will be assumed that a subscriber in the automatic main exchange desires to converse with a subscriber in the branch exchange. It will be assumed further that when the calling subscriber in the main exchange removes his receiver and dials the correct digits of the desired number, a well known Strowger selector with vertical and rotary motion, seizes the first idle trunk to the branch exchange.

Assuming that the trunk line shown is the first idle trunk accessible to the selecting switch, the wipers of said switch will then stop on bank contacts 427, 428 and 429. The switching relay 420 of the selecting switch will operate to connect the wipers of the selector to the bank contact, instantly establishing a circuit from ground through relay 440, contacts 441 and 421, bank contact 427, trunk conductor 463, contact 341, conductor 364, contact 254, high resistance relay 280, contacts 294 and 263, resistance coil 247, to battery. Relay 280 operates and closes a circuit to relay 210, from ground contacts 281 and 269, number 2 winding of relay 210 to battery. Relay 210 operates, lighting the busy lamp 217, from ground, contact 214, lamp 217 to battery. Relay 210 also closes ground through contact 213 to lead 259 thus providing guarding potential on the selector bank contacts of the outgoing switch multiple. Relay 210 closes another contact 211, to connect the tip 226 of the attendants switchboard jack with one conductor of the trunk cir-

cuit. A further contact on relay 210 contact 215, is closed to prepare a locking circuit to relay 290 and contact 216 closes a chain circuit. This trunk circuit is now held busy to outgoing calls even though ringing current may not as yet have been applied by the main office equipment. When the ringing period commences, the A. C. current is superimposed across the trunk from the main office through conductor 463, contact 311, conductor 364, condenser 289, alternating current relay 283, contact 271 to conductor 365, contact 312, conductor 464. Relay 280 remains operated but relay 283 operates and releases in response to the ringing and silent periods of the ringing current. During the first ringing period, relay 283 closes a circuit to operate relay 290, from battery, two windings of relay 290 in series, contacts 296, 285 and 233 to ground. These windings of relay 290 are of such a nature that winding number 2 overpowers winding number 1 sufficiently to allow the closure of contact 298 which short circuits winding number 1 and allows relay 290 to operate fully, closing its own locking circuit, from battery, number 2 winding, contacts 298, 215 and 223 to ground. This relay 290 will remain operated during the subsequent ringing periods and until its locking circuit is opened, either at contact 215 or contact 223. Another contact on relay 290, contact 291' closes to light the answer lamp, over a circuit from ground, contacts 291' and 255, answer lamp 218 to battery. Another contact 297, on relay 290 closes a multiple ground to the number 2 winding of relay 210 and a further contact 295, closes the circuit to relay 260, from ground, contact 281, contact 295, number 1 winding of relay 260 to battery. Relay 260 operates over this circuit and closes a part of its own locking circuit and changes the source of the holding ground of relay 210, from contact 281 on relay 280 to contact 275 on relay 270. During the first silent period which follows the first ringing period, as well as during all subsequent silent periods, relay 283 will release but relays 210, 260 and 280 will remain operated under the control of the high resistance relay 280, which as previously stated, will remain operated under the control of ground from the main exchange over the trunk conductor 364.

The branch exchange operator answers the call by inserting a plug into the jack J2. Ground through contact 229 over lead 367, winding number 1 to battery operates relay 320, which through contacts 321 and 322 closes a multiple connection for the trunk circuit. Ground at jack J2 through contact 229 also furnishes a holding ground for relay 210, to hold relay 210 in operated position for the period of the plug remaining in the jack. The closed loop of the plug circuit is now across the tip 226 and ring 225 of the jack J2 which causes relay 220 to operate over the following circuit: ground, number 2 winding of relay 220, one winding of repeating coil 256, contact 231, jack ring 225, plug ring 162, winding 174 of cord circuit repeating coil, contact 162, both windings of relay 120 in series, contact 161, winding 173 of repeating coil, tip 161 of plug, tip 226 of jack J2, contacts 211 and 234, one winding of repeating coil, winding number 1 of relay 220, to battery. Relay 220 operates and at contact 223 removes holding ground from relay 290 and through its contact 224 closes a loop across the trunk conductors, including the winding of relay 240, over the following circuit: ground, one winding of relay 440, contacts 441

and 421, bank contact 427, trunk conductor 463, contact 311, conductor 364, contacts 262 and 221, one winding of repeating coil 256, relay 240, a second winding of repeating coil 256, trunk conductor 365, contact 312, trunk conductor 464, bank contact 429, contacts 423 and 444 and, during the silent period, through contact 451 to battery causing relays 240 and 440 to operate. Contact 222 on relay 220 closes ground through winding of relay 259 to battery, operating relay 250. Relay 440 cuts off the ringing source and extends the trunk conductors 463 and 464 through contacts 442 and 443 and through the windings of the back bridge relay 470 to ground and battery respectively. Relay 240 operates and at contact 241 completes the locking circuit of relay 260. Relay 250 operates, opens contact 255 to extinguish the answer lamp 218, closes ground through contact 253 to the number 2 winding of relay 210 and through contact 254 of the impulsive circuit to the rotary magnet 370 of the adapter which will be referred to in connection with out calls, that is calls from branch exchange subscribers. Another contact 251 disconnects the winding of the high resistance relay 280 from the trunk conductor 364.

The trunk circuit is now ready for the branch exchange operator to speak with the calling party in the main exchange, which may be an automatic subscriber or an operator in a manual exchange. It should be noted that the plug might be inserted into the jack during the ringing period but the only ringing current which could reach the cord circuit and the operators receiver would be the amount which would be induced between the primary and secondary windings of the repeating coil. Thus, there would be less noise in the operators receiver, should the plug be placed in the jack during the ringing period, than would be the case in many previously designed circuits. The operator completes the connection to the wanted branch subscriber through the usual circuits, not shown.

After conversation is completed, both parties restore their receivers and the operator at the branch exchange removes the plug, the conditions then existing will depend upon which end of the trunk is released first.

We will assume that the main exchange disconnects first, which will open the circuit to relay 240. Relay 240 restores and at contact 241 opens the locking circuit to relay 260. Relay 260 restores, and at contact 262 opens one side of the trunk circuit and at contact 261 connects ground through relay 249 to conductor 365, that is, to the other conductor of the trunk. When one side of the trunk was opened at contact 262, the switch train in the main office restored to normal, after which a line equipment would be seized over the following circuit, busying the main exchange end of the trunk; ground, contacts 261 and 221, one winding of repeating coil, winding of relay 240, another winding of repeating coil, trunk conductor 365, contact 312, conductor 464, contact 416, relay 439 to battery. Relay 439 operates and places guarding potential on the selector bank multiple from ground through contact 431. Relay 240 again operates over this circuit and at contact 241 closes a circuit to operate relay 260, from battery, relay 260, contacts 241, 266 and 252, conductor 364, contact 311, conductor 463, contact 412 to ground at the trunk switch which has been seized by the operation of the line equipment. Thus, the trunk will be guarded until the operator re-

moves the plug to free the trunk for calls in either direction.

Should the operator remove the plug prior to the trunk being released by the calling party in main exchange, the following would take place; relay 320 in the adapter restores, the cord circuit loop holding relay 220 is opened allowing relay 220 to restore and at its contact 221 opens the trunk loop of the main exchange end giving disconnect supervision to the main exchange, this main exchange loop includes the winding of relay 240 which restores and at its contact 241 opens part of the locking circuit of relay 260. As relay 260 is being held in operated position from contact 274 on relay 270, the high resistance relay 280 will now be bridged across trunk conductors 364 and 365 and will operate on current, in either direction, from the main exchange. This bridge is maintained during the time between the restoring of relay 250 and the final release of the slow releasing relay 270. After relay 270 restores ground from contact 274 is removed from the number 1 winding of relay 260, which restores. Relay 280 is now connected to one trunk conductor and operates over the following circuit; battery, resistance coil 247, contacts 263 and 291, winding of relay 280, contact 251, trunk conductor 364, contact 311, conductor 463 to ground in the main exchange at the trunk switch which is still operated as this end of the trunk has not been released. From ground at contact 281 relay 210 is again energized and through its contact 213 connects ground to lead 259 which guards the branch exchange end of the trunk until the main exchange end is released to make the trunk free for calls in either direction.

The branch exchange subscribers have access to the trunk to the main exchange, through the multiple banks of the usual Strowger vertical and rotary type selector and connector switches. The subscriber dials the prearranged number to cause a selector to hunt and connect the subscriber's line to an idle trunk such as conductors 257 and 258. Conductor 259 is the usual control conductor. Subscribers may dial direct to other branch subscribers or to authorized numbers in the main exchange without assistance from the operator, although the operator may supervise such calls. However, should a branch exchange subscriber dial an unauthorized number, the trunk in combination with the adapter will operate to prevent the call reaching a subscriber in the main exchange, or to other unauthorized numbers, and the main exchange end of the trunk will be guarded until the calling subscriber abandons the call. The dial impulses from the calling subscriber's dial are repeated over the trunk to the main exchange through contact 221 and are repeated by contact 223 through contact 254 over conductor 369 to the rotary magnet 370 in the adapter. The wiper assembly of the adapter will step over its bank contacts in response to said impulses and, should an unauthorized number be dialed, relay 310 will operate to disconnect the trunk conductors 364 and 365 from leads 463 and 464 thus preventing any further impulses from being received on any main office switch. At the same time relay 310, at contact 313 connects ground to the trunk conductor 464 which operates the line equipment in the main exchange to cause this trunk to test busy to outgoing calls from main exchange subscribers. Due to the action of the weighted spring 317 on relay 310, there is a perceptible time interval between the opening of contacts 311 and 312 and the moment that relay

330 operates fully, to connect ground to conductor 464. During this time interval the main office switch train releases, after which the line equipment only operates to re-seize a switch and make the trunk test busy. After the adapter has operated and released the main office switch train, subsequently causing the line equipment in the main exchange to operate and guard the trunk, and until the calling subscriber ceases dialing, all of the additional impulses will operate relay 220. Contact 221 will relay these impulses to slow releasing relay 250, which will operate but due to its slow releasing characteristic, it will remain operated throughout the impulsive period and through its contact 254, will close a part of the circuit to relay 270. After the calling subscriber abandons the call, relay 220 will restore and at its contact 223 will complete the circuit to relay 270, which will operate, closing ground through contact 274 to energize relay 260. While relay 270 is being held by its slow releasing feature and after relay 250 restores, the high resistance relay 280 will be bridged across the trunk conductors 364 and 365 and will operate from the current, regardless of direction of flow of said current on these conductors, from the switch in the main exchange which has been seized by said line equipment. Relay 280, at its contact 281, closes ground to operate relay 210. Relay 210 immediately operates and through contact 213 places guarding potential on the bank multiple. Thus the period during which the bank multiple is unguarded is further shortened and when the last slow releasing relay has fully restored the trunk will be free for calls in either direction.

When it is necessary to allocate a trunk for the exclusive use of one branch exchange subscriber, for instance for through night service or special day service, the said subscriber's line is connected at the attendants' switchboard to a trunk by a patching cord, which may be simply a two conductor cord with a switchboard plug fitted at each end. When this is done, the following conditions would prevail; relay 210 will be held operated over the following circuit, ground, contact 229 of jack J2, number 1 winding of relay 210 to battery and at contact 213 will connect ground to lead 259 which prevents this particular trunk from being seized by a branch exchange selector, this same ground is extended to lead 366 in the adapter. Ground through contact 214, lamp 217 to battery lights the busy signal on the branch exchange operators' switchboard. When the trunk is seized at the main exchange, ground over conductor 364 operates relay 280. Following seizure ringing current is superimposed intermittently across the two conductors, operating relay 283, and at contact 284 ground from contact 229 is connected through contact 294 to relay 230 to battery, relay 230 operates on each impulse of ringing current. The operation of relay 230 closes contact 236 furnishing ground to operate relay 270 which in turn, through contact 274, operates relay 260. The operation of relay 270, opens at contact 271, the connection between relay 283 and the trunk lead 365 to allow the ringing current to follow the bypass circuit. The operation of relay 230 completes, at contact 233, a part of the bypass circuit for the ringing current to the subscriber's line. During the ringing period relays 283, 270, 260 and 230 are operated, in addition to relay 210 and one path for the ringing current may be traced over the following circuit: conductor 364, contacts 262 and 232, ring 225 of

5 jack J2 over one conductor of the patching cord one conductor of telephone line, telephone instrument, other conductor of telephone line, tip 226 of jack J2, contacts 211 and 235 to trunk conductor 365. Another path for ringing current is from conductor 364 through condenser 289, winding of relay 283, contact 233 to conductor 365. Relays 283 and 230 will operate during the ringing period and release during the silent period. However, relay 260 is now being held by a multiple ground at contact 281 through contact 268, winding of relay 260 to battery. Thus relay 280 is connected in bridge across the trunk and is being held by current from the switchboard at the calling end of the trunk, which may be automatic, manual or from a toll switchboard, also this direct current may be in either direction through the winding of relay 280. When the called subscriber removes his receiver to answer the call this places a loop across the circuit and should this occur during the ringing period, the loop would operate the back bridge relay in an automatic exchange or similar circuit at a manual switchboard. Should the called subscriber's receiver be removed during the silent period, the loop would operate relay 220 and at contact 221 close a circuit to connect relay 240 across the main exchange end of the trunk to operate the ring cut-off relay in the calling exchange. When relay 220 operates a second contact 222, is closed to operate relay 250, from ground, contact 222, winding of relay 250 to battery. The calling and called subscribers are now connected for conversation and the busy signal indicates to the operator of the branch exchange switchboard that the trunk is busy. After conversation is completed both subscribers restore their receivers thus causing the apparatus to return to normal as previously described. Calls from a line which is connected by a patching cord to a trunk line, will be made in the same manner as previously described, with the exception that a fewer number of digits will be dialed. As the telephone line is connected direct with the trunk, the removal of the receiver by a branch exchange subscriber causes a switch in the main exchange to be seized and the dialed impulse will directly operate the switches to complete the connection.

50 The above completes the description of the operation of the invention. What is considered new and is desired to have protected by Letters Patent is specifically stated in the appended claims.

55 What is claimed is:

1. In a telephone system, a two way trunk extending from a branch exchange to a main exchange, means for seizing the trunk and extending connections therover in either direction, a relay normally connected to one conductor of the trunk and operated when the trunk is seized at the main exchange to busy the trunk at the branch exchange, means responsive to the seizure of the trunk at the branch exchange for disconnecting said relay from said one conductor and for making the trunk busy at the main exchange end, and means responsive to the release of a connection extended over the trunk from the branch exchange for connecting said relay to both conductors of the trunk line to hold the trunk busy at the branch exchange until it is cleared at the main exchange.

2. In a telephone system, a two way trunk extending from a branch to a main exchange, means for extending a connection over the trunk in either direction, a relay normally connected to

one conductor of the trunk, means responsive to the extension of a connection from the branch to the main exchange for disconnecting the relay from said one conductor, means responsive to the initiation of the release of the connection at the 5 branch exchange for connecting said relay in branch exchange for connecting said relay in bridge of the trunk, said relay controlled thereafter from the main exchange to maintain the branch end of the trunk busy until cleared at main exchange.

3. In a telephone system, a two-way trunk extending from one exchange to another exchange, selector switches in said one exchange and automatic switches in said other exchange, means for operating a selector in said one exchange to seize 15 said trunk and extend a connection thereover to said other exchange, a relay normally connected from battery to one conductor of the other exchange section of the trunk line, means in said trunk responsive to said seizure of said trunk by 20 said selector switch for disconnecting said relay from said one conductor and connecting ground to the other conductor to seize one of said switches in the other exchange and make the other exchange end test busy, means in said trunk responsive to 25 the release by the subscriber in said one exchange for connecting said relay across said trunk conductors to guard said trunk at said other exchange.

4. In a telephone system, a two-way trunk extending from a branch to a main exchange terminating in an operator's position and multiple-contacts at said branch exchange, automatic contacts in the main exchange, means controlled 30 switches in the main exchange section of said trunk, means responsive to the seizure of said trunk by the operator at said position for seizing the 35 trunk and extending a connection thereover from the branch to the main exchange, a relay normally connected from battery to one conductor of the main exchange section of said trunk, means in said trunk responsive to the seizure of said 40 trunk by the operator at said position for disconnecting said relay from said one conductor and placing ground on the other conductor for seizing a switch in said main exchange and guarding the trunk, means in said trunk responsive to 45 the release of the trunk by said operator for connecting said relay across said trunk circuit to guard said trunk at the branch exchange multiple contacts and for seizing another switch at the main exchange to guard the main exchange 50 end of the trunk.

5. In a telephone system, a two-way trunk extending from a main to a branch exchange, terminating in automatic switches in the main exchange, in an operator's position and in multiple switch bank contacts at the branch exchange, means including said equipment for seizing the trunk and extending connections thereover in either direction, a high resistance relay normally connected from battery to one conductor of said trunk responsive to seizure by a switch at the main exchange, means responsive to the operation of said relay for busying said trunk at the branch exchange multiple switch bank contacts and for lighting the busy-lamp on the operator's switchboard, an alternating current relay in said trunk responsive to ringing current from the main exchange superimposed across both conductors of said trunk for lighting the answer lamp at said operator's position, and means in said trunk responsive to the operation of said alternating current relay to maintain the high resistance relay connected to one conductor of said trunk until the operator inserts a plug at the switchboard in the jack of the trunk, and means

responsive to the removal of said plug for connecting the said high resistance relay across the trunk to hold trunk busy at the branch exchange until cleared at the main exchange.

6. In a telephone system, a two-way trunk circuit extending from a branch exchange to a main exchange, means for seizing said trunk and extending connections thereover from a subscriber in the branch exchange to the main exchange, a relay normally connected from battery to one conductor of said trunk, an adapter associated with the trunk, means in said trunk, after seizure by a switch at the branch exchange, for operating the stepping switch of the adapter in accordance with the impulse sent from the calling subscriber's dial, means in said adapter responsive to specified groups of impulses from the calling subscriber's dial for opening both conductors of said trunk, removing the said relay from one conductor and connecting ground to the main exchange end of the other conductor for preventing any further impulses from passing to the main exchange and for seizing a switch at the main exchange to guard the trunk until the calling subscriber abandons the call.

7. In a telephone system, a two way trunk extending from a branch to a main exchange having an inductive connection therein, means for seizing the trunk from the main exchange end and means responsive to such seizure to busy the trunk at the branch exchange end and signal the operator at that end, a cord circuit at times connecting the trunk to a subscriber's line and means responsive to seizure of the trunk at the main exchange, in case said cord is in place, for preventing the operation of said signalling means and for completing a by pass around said inductive connection whereby the ringing circuit is extended to said cord circuit.

8. In a telephone system, a two way trunk extending from a branch to a main exchange having an inductive connection therein, means for seizing the trunk from the main exchange end and means responsive to such seizure to busy the trunk at the branch exchange end and signal the operator at that end, a cord circuit at times connecting the trunk to a subscriber's line, means responsive to seizure of the trunk at the main exchange, in case said cord is in place, for preventing the operation of said signalling means and for completing a by pass around said inductive connection whereby the ringing circuit is extended to said cord circuit, and means effective when the cord circuit is not in place for preventing any operation of said by passing means.

9. In a telephone system, a two way trunk extending from a branch to a main exchange having an inductive connection therein, means for seizing the trunk from the main exchange end and means responsive to such seizure to busy the trunk at the branch exchange end and signal the operator at that end, a cord circuit at times connecting the trunk to a subscriber's line, means including a ring down relay operated from the main exchange in case of seizure of the trunk at the main exchange, in case said cord is in place, for preventing the operation of said signalling means and for completing a by pass around said inductive connection whereby the ringing circuit is extended to said cord circuit, and means controlled by said by pass means for causing continued operation of said ring down relay as long as ringing current is applied to said trunk.
